(57) **CLAIM**

The ornamental design for an inspection camera housing, as shown and described.

DESCRIPTION

FIG. 1 is a top, rear perspective view of an inspection camera housing, showing my new design shown with broken line attachments;

FIG. 2 is another top perspective view thereof, in an unused state with the broken line attachments removed for ease of illustration;

FIG. 3 is a rear perspective view of FIG. 2;

FIG. 4 is a bottom perspective view of FIG. 2;

FIG. 5 is a front elevational view of the forward portion of FIG. 2, shown separately for ease of illustration;

FIG. 6 is a rear elevational view of the forward portion of FIG. 2, shown separately for ease of illustration;

FIG. 7 is a top plan view of the forward portion of FIG. 2, shown separately for ease of illustration;

FIG. 8 is a bottom plan view of the forward portion of FIG. 2, shown separately for ease of illustration;

FIG. 9 is a right side elevational view of the forward portion of FIG. 2, shown separately for ease of illustration;

FIG. 10 is a left side elevation view of the forward portion of FIG. 2, shown separately for ease of illustration;

FIG. 11 is a front elevational view of the rear portion of FIG. 2, shown separately for ease of illustration;

FIG. 12 is a rear elevational view of the rear portion of FIG. 2, shown separately for ease of illustration;

FIG. 13 is a top plan view of the rear portion of FIG. 2, shown separately for ease of illustration;

FIG. 14 is a bottom plan view of the rear portion of FIG. 2, shown separately for ease of illustration;

FIG. 15 is a right side elevational view of the rear portion of FIG. 2, shown separately for ease of illustration;

FIG. 16 is a left side elevation view of the rear portion of FIG. 2, shown separately for ease of illustration;

FIG. 17 is a top plan view of FIG. 1, shown in a state of use;

FIG. 18 is a top plan view of FIG. 1 shown in a state of use; and,

(Continued)

FIG. 19 is a top plan view of FIG. 1 shown in a state of use. The features illustrated in evenly-spaced dashed lines are included for illustrative purposes only to depict the environment of the inspection camera housing and form no part of the claimed design.
